US0D1051993S

(12) **United States Design Patent** (10) **Patent No.:** **US D1,051,993 S**
(45) **Date of Patent:** **** Nov. 19, 2024**

(54) **GAMING MACHINE**

- (71) Applicant: **AGS LLC**, Las Vegas, NV (US)
(72) Inventors: **Sigmund Lee**, Atlanta, GA (US); **Karl Frederick Zedell, Jr.**, Alpharetta, GA (US); **Rachel Calhoun Lewis**, Atlanta, GA (US); **Wei Gu**, Daly City, CA (US); **Ariel David Turgel**, San Francisco, CA (US); **Daniel Kendall Harden**, Palo Alto, CA (US)
(73) Assignee: **AGS LLC**, Las Vegas, NV (US)
(**) Term: **15 Years**
(21) Appl. No.: **29/739,228**
(22) Filed: **Jun. 23, 2020**

Related U.S. Application Data

- (60) Continuation of application No. 29/673,699, filed on Dec. 17, 2018, now Pat. No. Des. 888,834, which is

Primary Examiner — Ryan Harvey

(74) *Attorney, Agent, or Firm* — WEIDE & MILLER, LTD.

(57) **CLAIM**

The ornamental design for a gaming machine as shown and described.

DESCRIPTION

FIG. 1 is a top front perspective view of the claimed design; FIG. 2 is a front view of the claimed design of FIG. 1; FIG. 3 is a rear view of the claimed design of FIG. 1; FIG. 4 is a right side view of the claimed design of FIG. 1; FIG. 5 is a left side view of the claimed design of FIG. 1; FIG. 6 is a top plan view of the claimed design of FIG. 1; FIG. 7 is a bottom plan view of the claimed design of FIG. 1; FIG. 8 is a top front enlarged partial perspective view of detail 8 in FIG. 1; and, FIG. 9 is a front enlarged partial view of detail 9 in FIG. 2. The broken lines showing portions of the gaming machine depicts the boundaries of the claimed design and form no part of the claimed design.

1 Claim, 6 Drawing Sheets

Related U.S. Application Data

a continuation of application No. 29/631,063, filed on Dec. 27, 2017, now Pat. No. Des. 844,063, which is a division of application No. 29/540,241, filed on Sep. 22, 2015, now Pat. No. Des. 820,915.
